UNITED STATES PATENT OFFICE.

JOHN E. OSMER, OF OWOSSO, MICHIGAN, ASSIGNOR OF ONE-HALF TO LOUIS A. HARDIN, OF BOONE, IOWA.

FIRE-DOOR.

1,122,300.

Specification of Letters Patent. Patented Dec. 29, 1914.

Application filed February 2, 1914. Serial No. 815,912.

To all whom it may concern:

Be it known that I, JOHN E. OSMER, a citizen of the United States, residing at Owosso, Michigan, have invented certain new and useful Improvements in Fire-Doors, of which the following is a specification.

This invention relates to improvements in fire doors.

The main objects of this invention are: First, to provide an improved fire door which may be conveniently operated by air or steam, and one in which the mechanism is simple and compact. Second, to provide an improved fire door in which the door is effectively supported against pressure from within the fire box such as might be occasioned by the bursting of a flue. Third, to provide an improved fire door which may be locked open or partially open or closed, thereby permitting draft through the door and preventing its chattering and holding it open as may be desired.

Further objects, and objects relating to structural details, will definitely appear from the detailed description to follow.

I accomplish the objects of my invention by the devices and means described in the following specification.

The invention is clearly defined and pointed out in the claims.

A structure which is a preferred embodiment of my invention is clearly illustrated in the accompanying drawing forming a part of this specification, in which:

Figure I is a side view of a structure embodying the features of my invention. Fig. II is a front view of the structure shown in Fig. I, the lower end of the foot lever being broken away. Fig. III is a vertical section on a line corresponding to line 3—3 of Fig. II, parts being shown in full lines to better illustrate their form. Fig. IV is a detail vertical section on a line corresponding to line 4—4 of Fig. III. Fig. V is a detail horizontal section on a line corresponding to line 5—5 of Fig. III.

In the drawings similar reference characters refer to similar parts throughout the several views, and the sectional views are taken looking in the direction of the little arrows at the ends of the section lines.

Referring to the drawings, the door frame 1 is provided with an outwardly projecting housing comprising a top wall 2,

side walls 3 and bottom ledge or sill 4. The front of the housing is downwardly and inwardly inclined. The side walls are provided with inwardly projecting flanges 5 at the edges thereof, constituting door stops and supports for the door in its closed position. The upper parts of the side walls 3 of the housing are extended beyond the top wall at 6 so that the upper edge of the door 7 is between these projecting portions 65 and closes against the front edge of the top wall of the housing, see Figs. II and III. The door pivots 8 are arranged through suitable bosses in the side walls to engage the boss-like pintle knuckles 9 of the door. 70 The lower end of the door closes against and rests upon the sill portion 4. The door is curved in horizontal cross section as shown in Fig. V and is preferably corrugated on its inner side, the corrugations 75 10 being vertically disposed. This makes a very strong door structure. With the door thus supported in its closed position it is supported against pressure from the inside of the fire box and at the same time may be 80 readily opened. The door is provided with an upwardly projecting arm 11 secured to the lug 12 thereon. On the housing I mount a cylinder 13 having an inlet port 14 at its inner end, which is connected to the supply 85 pipe 15 through the valve casing 16 mounted on the inner head of the cylinder. The stem 17 of the valve 18 projects downwardly in position to be engaged by the lever 19, which is pivoted at 20 on the side 90 of the housing and provided with a foot piece 21 so that the lever may be operated as a foot lever. The rod 22 of the plunger 23 is connected to a forked lever 24 mounted by the pivot 25 on the top of the cylinder. 95 The arms 26 of the lever 24 project downwardly at the sides of the cylinder. The plunger rod is connected to the lever by means of the yoke-like link 27 which is secured to the end of the plunger rod by 100 the screw 28 and to the lever by suitable pivot connections. The lower ends of the arms of the lever are connected to the arm 11 on the door by the links 29. The lever is extended upwardly to provide a hand 105 piece 30 for hand operation. The rotation of the plunger on the cylinder is prevented by the screw 31 which engages a groove 32 in the under side of the plunger rod 22.

To retain the door in its open or closed or 110

partially open position I provide a catch pin 33 arranged to reciprocate through a suitable boss on the wall of the cylinder and engaging keeper notches 31 in the plunger rod, see Fig. III. For convenience in operation the catch is connected by the arm 35 to the valve actuating lever 19. The valve actuating lever is arranged so that there is lost motion in moving the lever to its valve engaging position. This permits the disengaging of the catch prior to the opening of the valve. It also permits the releasing of the catch without operating the valve to permit the closing of the door or its operation by means of the hand piece 30. The cylinder, may, if desired, be provided with an escape vent or valve, not shown, but, I find that, in practice, the air escapes from the cylinder with sufficient rapidity so that such vent or valve is not required.

It is not desired that the door shall drop shut freely, but that its closing shall be gradual. The plunger and cylinder acts as a dash-pot. The catch for retaining it in its closed position is of decided advantage as it is found that, under certain conditions, the doors, unless well secured, "chatter", owing to the effect of the draft thereon.

The door is well designed to withstand the action of the heat and in the event of an explosion within the furnace it cannot be blown out or from its hinges, unless the explosion is such as to practically destroy the furnace. This adds very greatly to the safety of the fireman and engineer, my improved fire door being especially designed for use on locomotives. The outwardly projecting housing protects the fireman when the door is open.

40 I have illustrated and described my improvements in detail in a simple and practical embodiment thereof. I have not at tempted to illustrate or describe various modifications which I contemplate, as I believe the disclosure made will enable those skilled in the art to which this invention relates, to adapt or embody the same as conditions may require. I desire, however, to be understood as claiming my improvements specifically in the form illustrated as well as broadly within the scope of the appended claims.

Having thus described my invention what I claim as new and desire to secure by Letters Patent, is:

1. In a fire door, the combination of a door frame comprising an outwardly projecting housing, a door pivoted at its upper end to swing upwardly and inwardly in opening, an upwardly projecting arm on said door, a cylinder mounted on said housing, a plunger, a plunger rod with keeper notches therein, a catch arranged to reciprocate through the wall of said cylinder to engage the notches of said plunger rod, a

forked lever pivotally mounted on said cylinder with its arms embracing the same, a yoke connecting said plunger rod with the arms of said lever, links connecting the arms of said lever with the arm on said door, an inlet valve for said cylinder, an operating lever for said valve, and connections for said lever to said catch, there being a lost motion connection for said lever and valve, whereby the catch is released upon the actuation of the lever prior to the opening of the valve.

2. In a fire door, the combination of a door frame comprising an outwardly projecting housing, a door pivoted at its upper end to swing upwardly and inwardly in opening, an upwardly projecting arm on said door, a cylinder mounted on said housing, a plunger, a plunger rod with keeper notches therein, a catch arranged to reciprocate through the wall of said cylinder to engage the notches of said plunger rod, a forked lever pivotally mounted on said cylinder with its arms embracing the same, a yoke connecting said plunger rod with the arms of said lever, links connecting the arms of said lever with the arm on said door, an inlet valve for said cylinder.

3. In a fire door, the combination of a door frame comprising an outwardly projecting housing, a door pivoted at its upper end to swing upwardly and inwardly in opening, an upwardly projecting arm on said door, a cylinder mounted on said housing, a plunger, a forked lever pivotally mounted on said cylinder with its arms embracing the same, a yoke connecting said plunger rod with the arms of said lever, links connecting the arms of said lever with the arm on said door, an inlet valve for said cylinder.

4. In a fire door, the combination of a door, an arm on said door, a cylinder, a plunger, a plunger rod with keeper notches therein, a catch arranged to reciprocate through the wall of said cylinder to engage the notches of said plunger rod, a forked lever pivotally mounted on said cylinder with its arms embracing the same, a yoke connecting said plunger rod with the arms of said lever, links connecting the arms of said lever with the arm on said door, an inlet valve for said cylinder, an operating lever for said valve, and connections for said lever to said catch, there being a lost motion connection for said lever and valve, whereby the catch is released upon the actuation of the lever prior to the opening of the valve.

5. In a fire door, the combination of a door, an arm on said door, a cylinder, a plunger, a plunger rod with keeper notches therein, a catch arranged to reciprocate through the wall of said cylinder to engage the notches of said plunger rod, a forked

lever pivotally mounted on said cylinder with its arms embracing the same, a yoke connecting said plunger rod with the arms of said lever, links connecting the arms of 5 said lever with the arm on said door, an inlet valve for said cylinder.

6. In a fire door, the combination of a door, an arm on said door, a cylinder, a plunger, a catch for said plunger, a pivotally 10 mounted lever, a link connecting said plunger rod and said lever, a link connecting said lever and the arm on said door, an inlet valve for said cylinder, an operating means for said valve, and connections for said valve 15 operating means and catch, there being a lost motion connection for said valve operating means and valve, whereby the catch is released prior to the opening of the valve and the catch may be released without opening 20 the valve.

7. In a fire door, the combination of a door, an arm on said door, a cylinder, a plunger, a catch for said plunger, a pivotally 25 mounted lever, a link connecting said plunger rod and said lever, a link connecting said lever and the arm on said door, an inlet valve for said cylinder.

8. In a fire door, the combination of a door, an arm on said door, a cylinder, a plunger, a catch for said plunger, a pivotally 30 mounted lever adapted as a hand lever, a link connecting said plunger rod and said lever, a link connecting said lever and the arm on said door, an inlet valve for said 35 cylinder, an operating means for said valve, and connections for said valve operating means and catch.

9. In a fire door, the combination of a door, an arm on said door, a cylinder, a plunger, a catch for said plunger, operating 40 connections for said plunger to said door, an inlet valve for said cylinder, an operating means for said valve, and connections for said valve operating means and catch, there 45 being a lost motion connection for said valve operating means and valve, whereby the catch is released prior to the opening of the valve and the catch may be released without opening the valve.

50 10. In a fire door, the combination of a door, an arm on said door, a cylinder, a plunger, a catch for said plunger, operating connections for said plunger to said door, an inlet valve for said cylinder, an operating 55 means for said valve, and connections for said valve operating means and catch.

11. In a fire door, the combination of a door frame comprising an outwardly projecting housing, a door pivoted at its upper end to swing into said frame, an arm on 60 said door projecting upwardly at the front of the housing, a cylinder mounted upon said housing, a plunger for said cylinder having a plunger rod reciprocating outwardly above said door, a forked lever pivotally mounted on said cylinder with its arms embracing the same, the upper end of the lever being adapted as a hand piece, a yoke embracing the front end of said cylinder, connecting the arms of said lever with 65 said plunger, links connecting the arms of said lever with said arm on said door, the said links being pivoted to the lower end of said lever arms, the pivots connecting said yoke to said lever arms being between the 70 lever pivot and the pivots connecting the links to said lever arms, and an inlet valve for said cylinder.

12. In a fire door; the combination of a door pivoted at its upper end to swing inwardly in opening, an upwardly projecting arm on said door, a cylinder mounted above the door, a plunger having a plunger rod reciprocating above the door, a forked lever 80 pivotally mounted on said cylinder with its arms embracing the same, a yoke connecting the said plunger to the arms of said lever, links connecting the arms of said lever to the arm on said door, the links being pivoted to the lower ends of the arm of the lever 85 and the yoke being pivoted to the lever between the link pivots and the lever pivot, and an inlet valve for said cylinder.

13. In a fire door, the combination of a door pivoted at its upper end to swing inwardly in opening, an upwardly projecting arm on said door, a cylinder mounted above the door, a plunger having a plunger rod reciprocating above the door, a pivotally 95 mounted lever, a link projecting inwardly 100 from the end of the plunger rod connecting said plunger rod to said lever, a link projecting inwardly from the arm of said door connecting said arm to said lever, and an inlet valve for said cylinder.

In witness whereof, I have hereunto set my hand and seal in the presence of two witnesses.

JOHN E. OSMER. [L.S.]
